(57) **CLAIM**

The ornamental design for a shooting target support stand, as shown and described.

DESCRIPTION

FIG. 1 Top plan view of the shooting target support stand thereof.

FIG. 2 Front elevation view of the shooting target support stand thereof.

FIG. 3 Bottom plan view of the shooting target support stand thereof.

FIG. 4 Right elevation view of the shooting target support stand thereof.

FIG. 5 Back elevation view of the shooting target support stand thereof.

FIG. 6 Left elevation view of the shooting target support stand thereof.

FIG. 7 Front isometric view of the shooting target support stand thereof.

FIG. 8 Back isometric view of the shooting target support stand thereof; and,

FIG. 9 Isometric view of a pair of the shooting target support stand, shown setup for use as described.

The components shown in broken lines of FIG. 9 represent the environment and do not comprise any part of the invention.

A shooting target support stand used in pairs to suspend a support beam and metal target.
